UNITED STATES PATENT OFFICE.

ROBERT T. JOHNSTON, OF CHICAGO, ILLINOIS, ASSIGNOR TO THE GOSS PRINTING PRESS COMPANY, OF CHICAGO, ILLINOIS, A CORPORATION OF ILLINOIS.

STEREOTYPE-PLATE.

1,126,768.

Specification of Letters Patent.

Patented Feb. 2, 1915.

Application filed May 23, 1913. Serial No. 769,391.

To all whom it may concern:

Be it known that I, ROBERT T. JOHNSTON, a citizen of the United States, residing at Chicago, in the county of Cook and State 5 of Illinois, have invented certain new and useful Improvements in Stereotype-Plates, of which the following is a specification, reference being had to the accompanying drawings.

10 My invention relates to stereotype-plates for rotary printing presses and has more particularly to do with plates designed to be prepared for the press after casting by passage through a suitable finishing machine. As is well known, such plates, after 15 being cast, must be beveled at their ends to receive the clamps by which they are secured on the press, and finishing machines as heretofore constructed are designed to do 20 that work. Such plates when cast are also provided with a riser or tail-piece, which is usually severed while the plate is being finished, the riser end of the plate being at 25 the same time beveled. When the plate is placed in the finishing machine it is necessary that means be provided for stopping it in proper relation with the end trimming cutters, after which it is clamped or locked 30 in place so that it will be held firmly while its ends are being beveled and the internal 35 ribs are being shaved, and considerable difficulty has heretofore been experienced in arranging the stops so that they would not interfere with the proper beveling of the plate ends.

My present invention has for its object to provide a new and improved stereotype-plate so constructed that the portions which are engaged by the stops do not have to be 40 beveled, and consequently interference of the stops with the beveling of the ends of the plate is avoided.

I accomplish this object as illustrated in the drawings and as hereinafter described.

45 In the accompanying drawings,—Figure 1 illustrates one form of my improved plate with the tail-piece attached, showing the form in which the plate is cast; and Figs. 2 and 3 are similar views showing different ways in which the same object may be accomplished.

50 In the plate shown in Fig. 1, 4 is the plate proper, and 5 the tail-piece or riser. As therein shown, the plate is cast with a riser 55 which does not subtend quite as great an

arc as the plate proper, so that shoulders 6 are formed at the riser end of the plate adjacent to the ends of what constitutes the beveled end portion of the plate after the riser is severed from it. The inner margin 60 of the beveled portion is indicated by a dotted line on Fig. 1. When the riser is severed, the severed end then presents the same appearance as that shown at the left-hand end of the plate illustrated in Fig. 2;— 65 that is to say, the beveled portion of the end does not subtend as great an arc as the plate proper, so that notches are formed in the end of the plate to receive the stops. It will be noted that in the construction shown in Fig. 70 1 the stops are at the following end of the plate instead of the leading end. When the plate is moved into the finishing machine its side margins rest upon the usual ledges or supports, and after the plate proper has 75 been inserted in the finishing machine it is drawn back slightly to bring the shoulders 80 6 against the stops and is then clamped in position. It will be obvious that the cutter which severs the riser from the plate does 85 not operate upon that part of the plate which is engaged by the stops and therefore its operation is not interfered with.

In Fig. 1 I have illustrated in dotted lines 90 a form of stop which may be employed in connection with the type of the plate there- 95 in shown. In said figure, 11 indicates a portion of one of the usual ledges or supports on which the side margins of the plate rest as it is moved into the finishing ma- 100 chine. 12 indicates a stop which projects upwardly at the rear end of one of the ledges 11, high enough to engage the shoul- 105 der formed by cutting away the plate. Said stop may be secured to the ledge 11 by a spring-plate 13 which is secured adjacent to one end thereof against the under side of the ledge 11, as shown. This is merely a suggested form of stop, as my invention 110 contemplates the use of any suitable form of stop.

In the form shown in Fig. 2, the plate is 115 designed to be engaged by the stops at its leading end, and therefore the plate is cast with notches 7 at its ends near its side mar- 120 gins, said notches lying opposite the ends of the beveled portion 8 of said plate, and in this construction the tail-piece may be co- 125 extensive in width with the plate proper and be severed in the ordinary way. In 130

Fig. 2 I have also shown in dotted lines a part of one of the ledges 13, with a stop 14 at the forward end thereof adapted to engage the leading end of the stereotype plate. This stop may be secured to the ledge 13 by a spring-plate 15 in the same way as that shown in Fig. 1.

In the form shown in Fig. 3, the stop is also intended to engage the leading end of the plate, but instead of providing notches 7 at the ends of the beveled portion 8 I provide a notch 9 intermediate of the beveled portion 10. In this figure I have shown a pivoted stop 16 in the form of a bellcrank pivoted at 17. If desired, a spring (not shown) may be employed in connection with the horizontal arm 18 of said stop to normally hold the operative portion of the stop in its upright position. The forms of stops shown in Figs. 2 and 3 are also merely suggested, as any other suitable stops may be used.

It will be observed that with each of the plates shown and described the end cutter 25 does not trim or bevel any portion of the plate that is engaged by the stop or stops, or, to put the matter in another way, the stop or stops engage a portion of the plate which does not have to be trimmed, and this 30 constitutes the salient feature of my present invention.

Copies of this patent may be obtained for five cents each, by addressing the "Commissioner of Patents, Washington, D. C."

By the construction described, the part engaged by the stop or stops is not cut off with the tail-piece, as is the case in some prior constructions, and the part of the plate 35 engaged by the stop does not project beyond the inner surface of the plate, which would be objectionable because it would interfere with the fitting of the plate on the press.

It will be understood that the term "cut 40 away," as used in the claims, has reference to the ultimate condition of the plate rather than to the manner in which the recess or notch which receives the stop is formed.

That which I claim as my invention, and 45 desire to secure by Letters Patent, is,—

1. A stereotype-plate for printing presses having a beveled end which forms a longitudinal extension thereof, a portion of the end of the plate adjacent to the beveled portion and in line therewith being cut away to receive a stop.

2. A stereotype-plate for printing presses having beveled ends which form longitudinal extensions thereof, a portion of one of the beveled ends being cut away to receive a stop.

ROBERT T. JOHNSTON.
